US00D581927S

(12) **United States Design Patent**
Sumii

(10) **Patent No.:** US D581,927 S
(45) **Date of Patent:** ** Dec. 2, 2008

(54) **ARITHMETIC AND CONTROL UNIT**

(75) Inventor: **Tetsu Sumii**, Tokyo (JP)

(73) Assignee: **Sony Corporation**, Tokyo (JP)

(**) Term: **14 Years**

(21) Appl. No.: **29/287,086**

(22) Filed: **Jun. 26, 2007**

(30) **Foreign Application Priority Data**

(57) **CLAIM**

The ornamental design for an arithmetic and control unit, as shown and described.

DESCRIPTION

FIG. 1 is a perspective view of a first embodiment of an arithmetic and control unit showing my new design;

FIG. 2 is a front elevational view thereof;

FIG. 3 is a rear elevation view thereof;

FIG. 4 is a left side elevational view thereof;

FIG. 5 is a right side elevational view thereof;

FIG. 6 is a top plan view thereof; and

FIG. 7 is a bottom plan view thereof.

FIG. 8 is a perspective view of a second embodiment of an arithmetic and control unit showing my new design;

FIG. 9 is a front elevational view thereof;

FIG. 10 is a rear elevation view thereof;

FIG. 11 is a left side elevational view thereof;

FIG. 12 is a right side elevational view thereof;

FIG. 13 is a top plan view thereof; and

FIG. 14 is a bottom plan view thereof.

FIG. 15 is a perspective view of a third embodiment of an arithmetic and control unit showing my new design;

FIG. 16 is a front elevational view thereof;

FIG. 17 is a rear elevation view thereof;

FIG. 18 is a left side elevational view thereof;

FIG. 19 is a right side elevational view thereof;

FIG. 20 is a top plan view thereof; and,

FIG. 21 is a bottom plan view thereof.

The broken lines represent various portions of the design and form no part of the claim. The dot-dash broken lines represent the boundaries of the design. None of the broken lines form any part of the claimed design.
